UNITED STATES PATENT OFFICE.

CARL AUGUST MAYER, OF SPRINGFIELD, MASSACHUSETTS, ASSIGNOR TO AMERICAN BOSCH MAGNETO CORPORATION, OF SPRINGFIELD, MASSACHUSETTS, A CORPORATION OF NEW YORK.

TIMING MECHANISM.

Application filed February 18, 1921. Serial No. 446,140.

To all whom it may concern:

Be it known that I, CARL AUGUST MAYER, a citizen of the United States, residing at Springfield, in the county of Hampden, State of Massachusetts, have invented certain new and useful Improvements in Timing Mechanism; and I do hereby declare the following to be a full, clear, and exact description of the invention, such as will enable others skilled in the art to which it appertains to make and use the same.

The present invention relates to an adjustable timing device for magnetos, and particularly one adapted to be carried by the interrupter housing of the magneto.

An ignition system almost invariably provides variable timing periods to suit different speed and load conditions imposed upon the engine with which it is associated.

To that end, the mechanical interrupter of the magneto or sparking coil has an adjustable member, to which is attached a timing member connected by an adjusting rod or wire to the control lever on the steering

wheel or post of an automotive vehicle or a convenient part of a stationary organization.

Heretofore, it has been customary to fasten a timing arm to the adjustable member of the interrupter by a screw or other securing means for rigidly connecting them together, but in such arrangement the adjusting pull

on the control lever is applied at a single point of the periphery of the adjustable member and sometimes causes the adjustable member to bind in its bearing, particularly if a decided increase in the resistance develops in the bearing.

It is often necessary for the timing member to be located on one side or the other of the adjustable member of the interrupter, or above or below it, or at some intermediate point, in order that the control lever may be attached to it most conveniently. The adjustable member is ordinarily in the form

of a ring carrying cams which are periodically engaged by the deflectable element of a pair of contact carrying elements. These cams are accurately positioned and fastened in the adjustable member, or cam ring, by

the manufacturer of the interrupter, and therefore, the engine builder is frequently inconvenienced in installing the magneto or the adjusting rod or wire. To meet this difficulty, the adjustable member or cam ring

of the interrupter has been provided with

slots into a selected one of which is set a lug carried by the timing ring surrounding the cam ring, and to the timing ring is attached a timing arm connected to the rod or wire, as above stated. While this arrangement provides for several positions of connection, it does not, however, provide for universal relative angular adjustability of the timing ring and cam ring, and it also requires a thicker adjustable member to provide for the slots. This results, as before, in a single point of application of the adjusting pull to the adjustable member. Furthermore, the timing ring is not positively prevented from working off from the adjustable member in an axial direction as a result of the continual vibration to which it is subjected by the engine.

The timing ring is usually rigid or integral with the timing arm, both having a common radial slit to permit a certain amount of flexing of the ring halves and the arm portions on each side of the slit in the arm. A clamping screw is used to flex the parts so as to clamp the ring halves upon the periphery of the cam ring. The pressure thus applied by the timing ring upon the cam ring forces the latter out of the true circular shape and a uniform result can never be produced due to the eccentricity of the rings upon the contraction of the split timing ring. Furthermore, such timing ring can grip the cam ring at only two points, or but a few points, around its circumference instead of substantially the whole circumference or periphery thereof. Such structure cannot meet the requirements of providing a connection adapted for all desired angular relations between the timing arm and the adjustable interrupter element nor the precise co-operation necessarily required in a magneto between the stationary and rotatable elements of the interrupter.

With the above in view and with the object of producing a simpler, cheaper and more efficient device, I have in accordance with one part of my invention devised an improved adjustable timing device comprising a flexible strap surrounding the ring and being secured at its ends to the flexible portions of the slotted arm, and preferably upon the tangential surfaces thereof, the flexible portions also having means to flex them for causing a tightening of the strap about the cam ring. As the flex-

ible portions are made to approach each other and the strap about the cam ring tightened, it will be apparent that the perimetral length of the strap tends to shorten, the forces applied to the ends thereof being transmitted tangentially of the periphery of the cam ring and throughout the length of the strap so that radial pressure is applied to the cam ring evenly or uniformly for the full extent of the contacting surfaces between the strap and cam ring.

As another part of the invention, whether or not the timing arm has arc-shaped portions and tangential surfaces, the strap and the cam ring are provided with mutually engageable means, preferably in the form of an annular groove in the periphery of the cam ring and a projection in the strap extending into such groove, for maintaining the strap and ring in fixed axial relation but to permit free relative angular movement.

As a further part of my invention, whether or not the timing arm has arc-shaped portions and tangential surfaces, the flexible portions of the timing arm are provided with projections which extend into, and are freely movable in, the groove formed in the cam ring so as to permit the universal relative angular movement between the timing arm and the cam ring but preventing relative axial movement thereof.

In the accompanying drawing illustrating the preferred embodiment of the invention:

Fig. 1 is an end view in elevation with the cam ring, timing arm and binding strap; Fig. 2 is a side view thereof; Fig. 3 is a top plan view thereof; Fig. 4 is a view in longitudinal section of the timing arm and binding strap and with the cam ring in plan; Fig. 5 is an end view of the timing arm and the binding strap, showing the projections thereon; and Fig. 6 is a fragmentary sectional view on an enlarged scale.

Referring more particularly to the drawing, an adjustable timing device constructed in accordance with my invention comprises a timing arm 1 being radially slotted to provide a slit 2 between the flexible portions 3 thereof, the flexible portions being preferably provided with arc-shaped ends 4, of the same curvature as the cam ring 5, for bearing against the periphery of the latter, as is clearly shown in Fig. 1. The flexible portions 3 also have faces 6 disposed in planes tangent to the periphery of the cam ring 5. The flexible portions 3 are also provided with axially aligned apertures 7 adapted to receive the binding screw 8, one of the apertures being suitably threaded to co-operate with the threaded portion of the screw. The cam ring has the usual cams 9 with which periodically engage the rotary deflectable elements of a mechanical interrupter in the usual manner.

Upon the surfaces 6 are connected the ends 10 of a flexible strap 11, this strap being relatively thin and of metal, the ends 10 being conveniently secured in place by means of screws 12.

The periphery of the cam ring 5 is preferably provided with an annular groove 13, the strap being preferably provided with an indented projection 14 extending into the groove 13 so as to prevent relative axial movement between the cam ring 5 and the strap 11 but permitting free relative angular movement between the strap and the cam ring, the projection being guided in the groove during such movement. The arc-shaped portions 4 are also preferably provided with ridges or projections 15 also fitting into the groove 13 for the purpose of preventing relative axial movement between the arm 1 and the cam ring 5 but also permitting the free relative angular movement between the arm and the cam ring; and also for the purpose of steadyng the timing arm laterally, the curved surface of the arc-shaped ends seating squarely upon the periphery of the cam ring in aid thereof.

It will be apparent that when the screw 8 is loosened, the portions 3 of the arm 1 are expanded. The strap 11 then may be placed over the periphery of the cam ring with the projection 14 of the strap and the projections 15 of the arm inserted in the groove 13. With the parts in the latter position, the arm 1 and the strap 11 may then be rotated angularly about the axis of the cam ring to any desired adjusted angular relation. When the screw 8 is turned to cause the flexing of the portions 3 toward each other, the ends 10 of the strap are thrown together or caused to move with a tendency to shorten the perimetral length of the strap about the cam ring 5. The forces acting on the ends of the strap 11 act in lines or planes tangential to the cam ring 5, thus causing a mutual and equal pull upon the ends 10, and with a resultant uniform contraction of the flexible strap 11 upon the cam ring 5 and a uniform distribution of the contacting pressure between the surfaces of the strap 11 and the ring 5. Inasmuch as the pressure intensity is uniform at all points, a much greater total pressure may be applied to the cam ring, without in any way affecting its true circular shape, and with sufficient engaging pressure to prevent relative angular movement by the vibration of the parts during the operation of the engine.

It is not necessary to remove the interrupter housing from the magneto, inasmuch as the device permits a movement of 360° for adjustment at any angular position by the mere loosening of the binding screw, the flexible strap being on the periphery of the cam ring and of substantially the same circumference thereof.

Having thus described my invention what I claim is:

1. In an adjustable timing device for magnetos having an interrupter housing including a cam ring having a groove, the combination of a slotted timing arm having flexible portions adapted to engage said ring, a flexible strip surrounding said ring and secured to the flexible portions of said slotted arm, means for flexing said flexible portions for tightening said strap about said ring, and a projection on said flexible portions of said arm extending into and movable along said groove in said ring.
2. In an adjustable timing device for magnetos having an interrupter housing including a cam ring, the combination of a slotted timing arm having flexible portions adapted to engage said ring, a flexible strap surrounding said ring and secured at its ends to said flexible portions of said slotted arm, and means for flexing said flexible portions for tightening said strap about said ring, an annular groove in said ring and a projection in said strap extending in said groove for maintaining said strap and ring in fixed axial relation, said strap and projection being adapted to move angularly, and projections on said flexible portions of said arm extending into and movable along said groove in said ring.
3. In adjustable timing devices for magnetos, the combination of a slotted timing arm having flexible portions, a cam ring, said flexible portions being arc-shaped to engage the periphery of said cam ring and having surfaces lying in planes tangent to said periphery of said cam ring, a strap surrounding said cam ring in smooth surface contact therewith and secured at its ends upon said surfaces of and to said flexible portions of said slotted arm, and means for flexing said flexible portions for tightening said strap about said cam ring.
4. In adjustable timing devices for magnetos, the combination of a slotted timing arm having flexible portions, a cam ring, said flexible portions being arc-shaped to engage the periphery of said cam ring and having surfaces lying in planes tangent to said periphery of said cam ring, a strap surrounding said cam ring in smooth surface contact therewith and secured at its ends upon said surfaces of and to said flexible portions of said slotted arm, means for flexing said flexible portions for tightening said strap about said cam ring, and mutually engageable means on said strap and said ring for maintaining the same in fixed axial relation.
5. In adjustable timing devices for magnetos, the combination of a slotted timing arm having flexible portions, a cam ring, said flexible portions being arc-shaped to engage the periphery of said cam ring and having surfaces lying in planes tangent to said periphery of said cam ring, a strap surrounding said cam ring in smooth surface contact therewith and secured at its ends upon said surfaces of and to said flexible portions of said slotted arm, means for flexing said flexible portions for tightening said strap about said cam ring, an annular groove in said ring and a projection in said strap extending in said groove for maintaining said strap and ring in fixed axial relation, said strap and projection being adapted to move angularly.
6. In an adjustable timing device for magnetos, the combination of a slotted timing arm having flexible portions, a cam ring having a groove, said flexible portions being arc-shaped to engage the periphery of said cam ring and having surfaces lying in planes tangent to said periphery of said cam ring, a strap surrounding said cam ring and secured upon said surfaces of said flexible portions of said slotted arm, means for flexing said portions for tightening said strap about said cam ring, and a projection on said flexible portion of said arm extending into and movable along said groove in said ring.
7. In adjustable timing devices for magnetos, the combination of a slotted timing arm having flexible portions, a cam ring, said flexible portions being arc-shaped to engage the periphery of said cam ring and having surfaces lying in planes tangent to said periphery of said cam ring, a strap surrounding said cam ring and secured at its ends upon said surfaces of and to said flexible portions of said slotted arm, means for flexing said flexible portions for tightening said strap about said cam ring, an annular groove in said ring and a projection in said strap extending in said groove for maintaining said strap and ring in fixed relation, said strap and projection being adapted to move angularly, and projections on said flexible portions of said arms extending into and movable along said groove in said ring.

In testimony whereof I affix my signature.

C. AUGUST MAYER.
